DISCONNECTING SWITCH

Joseph S. Thompson, Palo Alto, and Brian E. Menzies, San Mateo, Calif., assignors to Pacific Electric Manufacturing Corporation, San Francisco, Calif., a corporation of California

Application January 10, 1934, Serial No. 706,050

9 Claims. (Cl. 200—48)

The present invention relates to electrical switch apparatus, and more particularly to disconnecting switches of the type used in sectionalizing and interrupting high tension electrical 5 transmission lines.

An object of the invention is to provide an improved disconnecting switch and operating means which is adapted for use in connection with either a single or a multiphase circuit, where it is necessary to sectionalize a power transmission line, or to open or close a branch circuit at the point of intersection with the main line, or for the protection of any other electrical equipment that may be operated from an electrical high voltage 15 transmission line.

Another object of the invention is to provide an improved operating means for a disconnecting switch which can be easily and positively operated under all conditions of use.

20 Another object of the invention is to provide a spring type of counterbalancing means for a vertically movable electrical switch blade which will substantially counterbalance the blade in all its positions of operation without imparting any actuating force thereto.

A switch of the character contemplated by this invention is generally mounted in the open where it is subjected to bad weather conditions, and as a result it is necessary that the cooperating contacts of the switch be made so that they can be easily moved into and out of engagement with each other and at the same time provide a high contact pressure. Therefore, it is another object of the invention to provide an improved blade 35 and an improved operating mechanism which will move the blade into and out of cooperating relation with a stationary contact and produce a positive high pressure contact between the stationary contact and the movable switch blade.

40 A further object of the invention is to provide an improved blade for an electric switch which can be easily moved into cooperating relation with a stationary clip terminal and then into high pressure engagement therewith to thus insure a good electrical contact between the parts, when the switch is closed, without interfering with the closing movement of the switch blade.

With the above and other objects in view the invention resides in the construction, combination 50 and arrangement of parts substantially as hereinafter described and more particularly defined by the appended claims.

For a better understanding of the invention reference should be had to the accompanying 55 drawings, wherein there is shown by way of illus-

tration and not of limitation a preferred embodiment thereof.

In the drawings;

Figure 1 is a side elevation of a disconnecting switch constructed in accordance with this invention and mounted in an upright position, 5

Figure 2 is a view, similar to Figure 1, showing the switch mounted in an inverted position,

Figure 3 is an enlarged fragmentary view of the switch, illustrated in Figure 1, with parts 10 broken away and in section to show the position of the operating mechanism when the switch is in its closed position,

Figure 4 is a plan view of the switch as shown in Figure 3, 15

Figure 5 is a fragmentary side elevation partly in section showing the position of the operating mechanism when the switch is in its opened position,

Figure 6 is an end elevation taken from Figure 20 5, looking to the right,

Figure 7 is an enlarged fragmentary view showing details of the operating mechanism, and

Figures 8, 9 and 10 are side elevations partially 25 in section showing the details of the stationary contacts and the cooperating blade portions of switches constructed in accordance with the present invention.

In disconnecting and high tension switch installations, particularly where the switch is used 30 infrequently or is placed in the open where it is exposed to the elements, it is desirable that the switch be so constructed that the stationary contact and the movable switch blade will engage each other with a high contact pressure. At the 35 same time it is necessary that the high contact pressure producing means be of such a character that it will not interfere with the free closing and/or opening movements of the switch blade.

With the above and other requirements in view, the present invention contemplates a special form 40 of switch blade and cooperating contact and an improved actuating mechanism therefor which will operate to provide a high contact pressure 45 between the switch blade and the stationary contact after the switch blade has been moved into its final closed circuit position and which will also function to relieve the high pressure between the switch blade and the stationary contact before it becomes operative to move the switch blade into its opened circuit position.

For the purpose of illustration the invention, as shown in the drawings, is embodied in a single 50 pole switch. It is to be understood, however, that 55

the invention may be made applicable to multi-phase circuits by merely mounting any number of the single pole switches side by side upon a suitable support.

5 In the drawings 10 designates generally a switch operating mechanism constructed in accordance with the preferred embodiment of this invention and the numeral 11 designates generally a switch blade which is adapted to be moved into and out 10 of engagement with a stationary contact 12 by the switch operating mechanism 10. The stationary contact 12 is mounted upon the end of an insulating post 13 and the switch blade 11 is pivotally mounted upon a similar insulating 15 post 14. Disposed in spaced relation with the insulating post 14, there is an insulating post 15 which is adapted to control the switch operating mechanism 10. The insulating posts 13 and 14 are rigidly secured in spaced relation upon 20 a suitable support 16, such as the structural iron frame work of a transmission tower, and the insulating post 15 is journaled upon the support 16 so that it may be rotated about its axis, by means of a worm 17 and a worm gear 18, to 25 control the switch operating mechanism 10, as will hereinafter appear.

In Figure 1 of the drawings the switch is shown as mounted in an upright position above the support 16 and in Figure 2 of the drawings 30 it is shown as suspended below the support 16. In each of these arrangements, except for the difference in a switch blade counterbalancing means which is to be described in detail herein-after, the several elements of the switch blade 35 and its operating mechanism are identical in form and mode of operation.

For a more detailed description of the switch operating mechanism 10 and the switch blade 11, reference is now made to Figures 3, 4 and 5 of 40 the drawings. As here shown, the switch blade 11 is formed of a length of copper tubing 19 carried by a supporting member 20 and at its outer end it has a stirrup like member 21 which is adapted to move into circuit establishing 45 relation with the stationary contact 12. The supporting member 20 is pivotally mounted upon a transversely disposed shaft 22 carried by a cap 23 upon the insulating post 14. Extending through the switch blade 11 there is a push 50 rod 24 which carries a contact pressure producing foot 25 at its outer end. The contact pressure producing foot 25 is disposed opposite and in spaced relation with the end or bottom of the stirrup like member 21 so that an outwardly extending portion 26, upon the stationary contact 12, can project therebetween. The other end of the push rod 24 is connected to a switch operating lever 27, by means of a clevis 28, so that 55 it will operate to move the contact pressure producing foot 25 into clamping engagement with the extending portion 26, upon the stationary contact 12, after the stirrup like member 21 has been moved into its final switch closed position. The switch operating lever 27 pivots about the shaft 60 22 and projects upwardly through the blade supporting member 20 and has a limited free movement between spaced abutments or stops 29 and 30 carried thereby. Extending between the upper end the switch operating lever 27 and an 65 operating crank arm 31, carried by the rotatable insulating post 15, there is a link 32. This link 70 32 is connected at its ends to the switch operating lever 27 and to the crank arm 31 by means of two cooperating clevis members 33 and 34 75 and it is made adjustable in length by means of

screw threads and a lock nut 35 at each end thereof.

For the purpose of holding the insulating posts 14 and 15 in properly spaced relation and preventing a lateral strain being imposed thereupon 5 by an operation of the switch, there is a pair of spaced stay rods 36. These stay rods 36 are connected at one end to the cap 23, upon the insulating post 14, and at the other end they are secured to a journal forming member 37, 10 through which extends a stub shaft that carries the crank arm 31, at the upper end of the insulating post 15. In order to further relieve the rotatable insulating post 15 of strain, and particularly a twisting strain, by a turning of the 15 crank arm 31, there is provided a switch blade counterbalancing spring 38. The spring 38 is enclosed in a cylinder 39 which is pivotally secured to a supporting arm 40 carried by the journal forming member 37. Projecting through the 20 free end of the cylinder 39 and cooperating with the spring 38, there is a rod 41 having a piston like head 42. The outer end of the rod 41 is pivotally connected to an upwardly extending arm 43 carried by the supporting member 20 25 and, as shown in all but Figure 2 of the drawings, the spring 38 is disposed between the piston like head 42 and the free end of the cylinder 39 so that it will be compressed when the rod 41 is under tension. In Figure 2 of the drawings, 30 because of the inverted position of the switch, the piston like head 42 is shown as located intermediate the ends of the rod 41 and the spring 38 is shown as disposed between the piston like head 42 and the pivoted end of the cylinder 39. With 35 this latter arrangement the spring 38 will be compressed and its effective leverage arm decreased as the switch blade 11 moves downwardly into its open circuit position. The spring 38 is so constructed and disposed with respect to the 40 axis of the shaft 22 that, in each arrangement, it will substantially counterbalance the weight of the switch blade 11 in all positions between its limits of movement. In other words, when the switch blade 11 is in the position shown in Figure 45 3 of the drawings, the spring 38 will exert a force upon the arm 43 sufficient to counterbalance the switch blade 11 and its component parts and as the switch blade 11 moves upwardly the leverage, provided by the arm 43 and the force exerted by 50 the spring 38, will decrease in direct proportion to the decreasing spring load exerted by the switch blade 11 as its center of gravity moves toward the pivotal point upon the shaft 22. If 55 the switch is mounted in an inverted position, as shown in Figure 2 of the drawings, the counterbalancing pressure exerted by the spring 38 will increase as the switch blade 11 moves downward and, because of the decreasing leverage action resulting from the rotation of the arm 43, it is 60 possible to construct and arrange the spring 38 so that it will substantially counterbalance the weight of the switch blade 11 throughout its downward and upward movements.

When the crank arm 31 is turned by rotation of the insulating post 15 to open the switch, the link 32 will move the switch operating lever 27 in a counter-clockwise direction against the abutment 30 upon the supporting member 20 and at the same time move the contact pressure producing foot 25 out of contact with the extending portion 26 upon the stationary contact 12. When the switch operating lever 27 engages the abutment 30 and the contact pressure producing foot 25 has been retracted, the parts will be held in 75

this position by a latch 44 which cooperates with a projection 45 upon the clevis 28. Under these conditions, the switch blade 11 may be again fully closed by a reverse or counter-clockwise movement of the switch operating lever 27 without any lost motion of the lever and without having to overcome any retarding force due to a frictional engagement between the switch blade 11 and the stationary contact 12, as is now the usual practice.

In Figures 6 and 7 of the drawings the latch 44 is shown as pivotally mounted upon the supporting member 20 and as biased into an operative position by means of a spring 46. The latch 44 has an oppositely projecting foot 47 that engages an adjustable stop 48 which will cause it to disengage the projection 45 upon the clevis 28 when the switch blade 11 approaches its final circuit closing position. This will release the push rod 24 and the switch operating lever 27 and permit the lever to become effective, during a final switch closing movement of the crank arm 31, to exert a pressure upon the push rod 24 and thus move the contact pressure producing foot 25 into contact with the extending portion 26 and clamp it against the end or bottom of the stirrup like member 21 to provide a high contact pressure therebetween.

The crank arm 31 is of such a length that it will move through an arc of slightly more than 180 degrees and pass over center with respect to the axis of the insulating post 15 to produce, in conjunction with the link 32, a toggle like action which will serve to lock or hold the switch blade 11 in its closed or fully opened position.

The journal forming member 37, at the upper end of the insulating post 15, has an outwardly projecting conductor terminal supporting boss 49, by means of which the switch can be connected in a circuit. In order to provide a low resistance path, between the boss 49 and a similar terminal supporting boss 50 carried by the stationary contact 12, the stay rods 36 are made of good current conducting proportions and at 45 their inner ends they connect with braided flexible conductors 51 which are clamped to the underside of the supporting member 20 in good electrical contact with the copper tubing 19 of the switch blade 11.

In Figure 8 of the drawings there is shown a modified form of stationary contact which has a pivotally mounted extending tongue 52. The tongue 52 is carried upon an insulator cap engaging plate 53 by means of a shaft 54 and is biased in an outward direction by a spring 55 located at one side of the shaft 54. A stirrup like member 56 is here shown as having an integrally formed dome like cover 57 disposed over the tongue 52. The outer surface of the tongue 52 is curved so that it will be moved against the action of the spring 55 as the stirrup like member 56 moves into engagement therewith and thus the contacting surfaces will be brought together with a wiping action. At the bottom of the tongue 52 there is a projection 58 which cooperates with a stop 59 upon the plate 53 to limit the outward displacement of the tongue 52 when the stirrup like member 56 is moved out of engagement therewith. Projecting outwardly from the plate 53 there is a conductor terminal supporting boss 60 and connected between the tongue 52 and a point closely adjacent the boss 60 there is a flexible conductor 61 which serves to conduct the current carried by the switch from the tongue

52 directly to the switch terminal. As an additional adjunct, the plate 53 carries a bracket 62 having a pair of flared and spaced guides 63 which are adapted to engage the switch blade 11 and guide the stirrup like member 56 over the tongue 52.

In Figure 9 of the drawings there is shown a stationary terminal, designated by the numeral 64, which is similar in every respect to the stationary contact 12, previously described, except that the upwardly extending portion thereof is provided with a recess 65 on its inner side at the point where the contact pressure producing foot 25 engages therewith. When a terminal of this character is used and the contact pressure producing foot 25 is moved into the recess 65 by the final movement of the switch operating lever 27, the switch blade 11 will be securely held and locked at its outer end against any circuit opening movement. This arrangement will be found particularly desirable where the switch is mounted in an inverted position, as illustrated in Figure 2 of the drawings.

The arrangement shown in Figure 10 of the drawings is identical to that illustrated in Figure 1 of the drawings, except that a yielding connection is provided between the contact pressure producing foot and its controlling push rod. The yielding connection can be provided for in a number of different ways. As here shown, the switch blade 11 is provided with a push rod 66 having a slidably mounted contact pressure producing foot 67 upon its end. There is a compression spring 68 interposed between the end of the push rod 66 and the contact pressure producing foot 67. This spring 68 is made very stiff and of a few turns so that it will come into action only during the final movement of the push rod 66. In order to prevent a turning of the contact pressure producing foot 67 and a displacement thereof, it is secured to the push rod 66 by a pin 69 which passes through an elongated transversely extending slot 70 formed in the end of the push rod 66.

In Figures 1, 3, 9 and 10 of the drawings, the stirrup like member 21 is shown as having a removable cover 71 which serves to protect the switch contacts against rain, sleet, snow, or the accumulation of dirt and other foreign matter at this point.

For safety, a switch of the character contemplated by this invention will be mounted in an elevated position upon a pole or a structural steel tower. Therefore, some provision must be made for driving the worm 17 which rotates the insulating post 15. If the switch is to be manually operated, this can be accomplished by a sprocket and downwardly depending chain arrangement that connects with the shaft upon which the worm 17 is mounted, or by a downwardly extending shaft having a crank at its lower end. In this latter arrangement the downwardly extending shaft may be connected to the shaft which supports the worm 17 by means of beveled gears or a universal joint. If desired, the worm 17 may be connected directly to an electric motor and remotely controlled by push buttons or relays.

The operation of the switch, illustrated in the drawings, may be described as follows:

When the switch is in its circuit closed position, as shown in Figure 3 of the drawings, and the insulating post 15 is rotated by any of the above or other means, the crank arm 31, carried thereby, will exert a pull upon the link 32 and cause the switch operating lever 27 to rotate

clockwise about the shaft 22. As the switch operating lever 27 is thus rotated, it will move the contact pressure producing foot 25 to disengage the outwardly extending portion 26 of the stationary contact 12. This initial movement of the switch operating lever 27 will release the contact pressure between the engaging contacts of the switch and permit the switch blade 11 to be easily moved into an open circuit position. During this movement, the switch operating lever 27 will move independently of the switch blade supporting member 20 until it reaches the abutment 30 carried thereby. After the switch operating lever 27 engages the abutment 30, upon the supporting member 29, it will operate to raise the switch blade 11 by rotating the supporting member 20 about its shaft 22. As soon as the supporting member 20 has rotated upwardly a sufficient distance to carry the oppositely projecting foot 47, carried by the latch 44, out of engagement with the adjustable stop 48, the latch 44 will be moved by the spring 46 into engagement with the projection 45, carried by the clevis 28. This will lock the contact pressure producing foot 25 in a retracted position and also secure the switch operating lever 27 against the abutment 30 until the switch blade 11 is again operated into its circuit closing position.

During the above movement of the switch blade 11, the spring 38 will expand and, because of its angular disposition with respect to the shaft 22, its effective lever arm will decrease as the switch blade 11 approaches a vertical position. As a result, the spring 38 will substantially counterbalance the weight of the switch blade 11 and relieve the crank arm 31 of all effort, except that which will be required to impart movement to the switch blade 11. When the crank arm 31 rotates to open the switch, it will move in an arc slightly over 180 degrees or, in other words, just over the center of the insulating post 15 and, in conjunction with the link 32, provide a toggle like action which will serve to hold the switch in its vertical position until it is again turned in an opposite direction by a rotation of the insulating post 15.

After the switch has been fully opened, the several parts thereof will be locked in the positions shown in Figure 5 of the drawings. When the parts are in this position, the switch can then be closed by rotating the insulating post 15 in a reverse direction. This will turn the crank arm 31 out of its over center position, so that it will operate through the link 32 to move the switch operating lever 27 in a counter-clockwise direction and, because of the latch 44, move the supporting member 20 in the same direction to carry the switch blade 11 downwardly into its circuit closing position. As the supporting member 20 moves downwardly, it will also bring the oppositely projecting foot 47, upon the latch 44, into engagement with the adjustable stop 48 and thus cause the latch 44 to move out of engagement with the projection 45 to release the push rod 24 and the switch operating lever 27, so that the latter can operate through an additional arc, independently of the supporting member 20, to force the contact pressure producing foot 25 into engagement with the outwardly extending portion 26, on the stationary contact 12, and clamp it against the bottom of the stirrup like member 21 to provide a high contact pressure therebetween.

While we have, for the sake of clearness and 75 in order to disclose the invention so that it can

be readily understood, described and illustrated specific devices and arrangements, it is to be understood that this invention is not limited to the specific means disclosed, but may be embodied in other ways that will suggest themselves to persons skilled in the art. It is believed that this invention is new and it is desired to claim it so that all such changes as come within the scope of the appended claims are to be considered as part of this invention. 10

Having thus described our invention, what we claim and desire to secure by Letters Patent is—

1. In a high tension disconnecting switch, the combination of a stationary contact, a switch blade support mounted in spaced relation with said stationary contact, a tubular switch blade pivotally mounted upon said support, a contact member at the end of said switch blade adapted to move into and out of engagement with said stationary contact, a contact pressure producing means opposite the contact member at the end of said switch blade, an operating lever journaled upon said switch blade support for moving said switch blade and its contact member into and out of engagement with said stationary contact and also operating said contact pressure producing means, an operating rod extending through said tubular switch blade and connected between said contact pressure producing means and said operating lever, a latch carried by said switch blade support and operating upon said rod for preventing an operation of said contact pressure producing means by said lever when the switch blade is in all but its circuit closing position, and means in the path of movement of said switch blade carrying member for releasing said latch and rendering said lever operative through said rod to exert a direct force upon said contact pressure producing means to provide a high pressure contact between said stationary contact and said contact member only when the switch blade is in its circuit closing position. 30

2. In a disconnecting switch, the combination of a support, a switch blade carrying member pivotally mounted upon said support, a tubular switch blade carried by said member, a stationary contact disposed in spaced relation with said support, a contact making member upon the end of said switch blade adapted to engage one side of said stationary contact, a contact pressure producing member at the end of said switch blade adapted to engage the other side of said stationary contact and cooperate with said contact making member and to produce a high contact pressure between said contacts, an operating lever pivotally mounted upon said support for exerting a pressure upon said pressure producing member and having a limited free travel with respect to said switch blade carrying member, an operating rod extending through said tubular switch blade and connected between said pressure producing member and said operating lever, a latch upon said switch blade carrying member for securing said operating lever to said switch blade carrying member when it reaches one of its limits of free travel, to thereby establish a positive switch operating connection between said operating lever and said switch blade carrying member, and means carried by said support for rendering said latch inoperative when the switch blade is in its circuit closed position and permitting said operating lever to apply direct and positive pressure through said rod and upon said contact pressure producing mem- 75

ber after the switch blade has reached its final closed position upon said stationary contact.

3. In a disconnecting switch, the combination of a support, a switch blade carrying member 5 pivotally mounted upon said support, a tubular switch blade carried by said member, a stationary contact disposed in spaced relation with said support, a contact making member disposed centrally upon the end of said tubular switch blade 10 adapted to engage the outside of said stationary contact, an operating rod extending through said tubular switch blade, a contact pressure producing member disposed opposite and in co-operating relation with said contact making 15 member upon the end of said operating rod and adapted to be moved against the inside of said stationary contact, an operating lever pivotally mounted upon said support and connected to the other end of said rod for moving said pressure 20 producing member into and out of engagement with said stationary contact, a latch upon said switch blade carrying member for securing said operating lever to said switch blade carrying member to prevent a movement of said operating 25 rod and the contact pressure producing member and also establish a positive switch operating connection independently of said rod between said operating lever and said switch blade carrying member, and means for rendering said 30 latch inoperative when the switch blade is in its circuit closed position to permit said operating lever to apply direct pressure to said rod and move said contact pressure producing member against and away from said stationary contact 35 respectively during the final switch closing and the initial switch opening movement thereof.

4. In a disconnecting switch, the combination of a pivotally mounted switch blade carrying member, a tubular switch blade carried by said member, a stirrup like contact member at the end of said tubular switch blade, a stationary contact adapted to project into and engage the inside surface of said stirrup like contact member, a rod extending through said tubular switch 45 blade, a contact pressure producing foot at the outer end of said rod adapted to engage said stationary contact, a lever pivotally mounted upon the same axis with said switch blade carrying member having a limited freedom of movement with respect to said switch blade carrying member for moving said rod through the tubular switch blade and causing said contact pressure producing foot to engage and disengage said stationary contact, a latching means 50 for securing said lever to said switch blade carrying member and preventing said freedom of movement when said contact pressure producing foot is out of engagement with said stationary contact, and means for rendering said latching 55 means inoperative when said stirrup like contact member has again moved into engagement with said stationary contact.

5. In a disconnecting switch, the combination of a support, a switch blade carrying member 65 pivotally mounted upon said support, a tubular switch blade mounted upon said member, a stirrup like contact member secured upon the end of said tubular switch blade having an inside contact making surface, a stationary contact adapted to project into said stirrup like contact member and engage the inside contact making surface thereof when the tubular switch blade is 70 in its circuit closed position, a push rod extending through said tubular switch blade having a 75 pressure producing foot at the end thereof

adapted to engage said stationary contact, a lever pivotally mounted upon said support for moving said switch blade carrying member and the tubular switch blade carried thereby to open and close the switch, said lever having a limited movement independent of said switch blade carrying member and said tubular switch blade, whereby it can operate upon said push rod and move said pressure producing foot against said stationary contact to establish a high pressure 10 engagement between the contact making surface of said stirrup like contact member and said stationary contact when the tubular switch blade is in its final closed position, and means for locking said lever against a movement independent of said switch blade carrying member in all but the closed position of said tubular switch blade.

6. In a disconnecting switch, the combination of a circuit controlling switch blade, a pivotal support for said switch blade about which it will move in a vertical plane, a lever means for operating said switch blade from a circuit closing to a circuit opening position and vice versa, said lever means having a limited free movement 20 independent of the switch blade at the initial opening and final closing positions of the switch blade, a contact pressure producing means operable by said lever during its independent movement, spring means connected to said 25 switch blade at a point removed from its pivotal axis and operating independently of said switch blade operating lever means for counterbalancing the weight of said switch blade in all its positions without exerting any operating force upon 30 the switch blade during an operating movement thereof, whereby said switch blade will remain stationary when said lever means moves independently of the switch blade to control said pressure producing means during the initial 35 opening and final closing operation of said lever means, and a latch at the pivoted end of said switch blade operable to secure said lever means against free movement independent of said switch blade in all but the closed position of said 40 switch blade.

7. In a disconnecting switch of the character described, the combination of a stationary switch blade support, a blade supporting member pivotally mounted upon said stationary support, 50 a switch blade carried by and extending outwardly from said member adapted to move in a vertical plane and engage a spaced stationary contact, a contact pressure producing means carried by said switch blade, a lever pivotally mounted upon said stationary support independently of said member adapted to operate said contact pressure producing means when said switch blade is in its circuit closing position, an abutment upon said pivotally mounted 55 member against which said lever will engage when in an inoperative position with respect to said pressure producing means, and a latch carried by said member for securing said lever against said abutment when said switch blade is 60 in all but its final circuit closing position.

8. In a disconnecting switch of the character described, the combination of a stationary switch blade support, a blade supporting member pivotally mounted upon said stationary support, 70 a switch blade carried by and extending outwardly from said member adapted to move in a vertical plane and engage a spaced stationary contact, a contact pressure producing means upon the contact engaging end of said switch 75

- blade, a lever pivotally mounted upon said stationary support independently of said member, an operating rod connected between said lever to said pressure producing means adapted to operate said contact pressure producing means when said lever moves independently of said switch blade, an abutment upon said pivotally mounted member against which said lever will engage when in an inoperative position with respect to said pressure producing means, and a latch carried by said member for securing said lever against said abutment when said switch blade is in all but its final circuit closing position.
15. 9. In a disconnecting switch of the character described, the combination of a stationary switch blade support, a blade supporting yoke pivotally mounted upon said stationary support, a switch blade carried by and extending outwardly from said yoke adapted to move in a ver-

tical plane and engage a spaced stationary contact, a contact pressure producing means upon the contact engaging end of said switch blade, a lever pivotally mounted upon said stationary support independently of said yoke for opening and closing said switch blade, a rod extending from said lever to said pressure producing means adapted to operate said contact pressure producing means when said lever moves independently of said switch blade, an abutment upon said pivotally mounted yoke against which said lever will engage when in one extreme of its independent movement, and a latch carried by said yoke for securing said lever against said abutment and independent movement when said switch blade is in all but its final circuit closing position.

JOSEPH S. THOMPSON.
BRIAN E. MENZIES.
